W. H. Finney

Attorney.

UNITED STATES PATENT OFFICE.

MARTIN BOCK, OF MAPLE SHADE, NEW JERSEY.

SOAP HOLDER.

Application filed October 31, 1923. Serial No. 671,889.

To all whom it may concern:

Be it known that I, MARTIN BOCK, a citizen of the United States, residing at Maple Shade, in the county of Burlington and State of New Jersey, have invented a certain new and useful Improvement in Soap Holders, of which the following is a full, clear, and exact description.

The object of this invention is to provide a pad or holder on which a cake of toilet or other soap may be laid to drain and dry off after using, the device being adapted for use on porcelain or other washstands, tubs and sinks, and capable of being used in the cavity that is found in some such washstands to receive soap and provided with a drain connection.

The invention consists of a soap holder made of soft or flexible rubber with rows of teeth arranged across the same or lengthwise of the same and capable of supporting a cake or piece of soap above the bottom of the holder so that the air may pass beneath it to aid in drying the soap after use, as I will proceed now to explain and finally claim.

In the accompanying drawings illustrating the invention, in the several figures of which like parts are similarly designated, Figure 1 is a perspective view, Fig. 2 is a longitudinal section on line 2—2 of Fig. 1, and Fig. 3 is a transverse section on line 3—3 of Fig. 1, illustrating one form of holder made in accordance with this present invention. Fig. 4 is a longitudinal section of another form of the invention. Fig. 5 is a longitudinal section in which different forms of teeth alternate. Fig. 6 is a cross section illustrating flat valleys between the rows of teeth as distinguished from the curved valleys shown in the other figures, and also illustrating a holder in which the teeth on opposite sides are alike.

1 is a body of rubber or other flexible and plastic or moldable material of waterproof character, and having the circumferential rim 2, provided with serrated edges 3, 3, and of a height at 4, 5 and 6 less than the height of the remainder of the rim. Between the serrated rim portions 3 are arranged the longitudinal ridges 7 also toothed or serrated, and preferably in the same manner as the rim. Between the toothed portions 3, 3 and 7, 7 are concave valleys 8 which serve to catch drippings from the soap and

from which the drippings may be readily removed and the holder cleaned.

In the use of my holder, the cake of soap after use is laid on the edges of the toothed rim 3 and ridges 7 to drain and dry off. The portions 4, 5 and 6 at opposite ends as well as the spaces between the teeth and beneath the soap provide for the passage of air beneath the soap so as to aid in drying it.

As will be observed, the teeth are double-dented, and this for the purpose of insuring a better hold on the soap and to prevent its accidental escape therefrom should the holder be tilted or moved out of position.

The holder may be provided with the toothed rim and ridges on both sides of the body, as indicated in Figs. 4 and 6. In the illustration shown in Fig. 4, the same sort of teeth are used as those shown in Figs. 1, 2 and 3, while on the opposite side the teeth 9 are single dents. As shown in Fig. 5, the toothed or serrated rim and ridges may have not only teeth of the same kind but these parts may have both forms of teeth, the double-dented 10 and the single-dented 11 in alternation. The construction shown in Fig. 5 also may have opposite sides of the body provided with the toothed rim and ridges, the teeth being of the same or different sort on opposite sides.

As shown in Fig. 6, the valleys 12 may be flat instead of concave; and obviously the invention is not limited to the peculiar shape or conformation of the valleys so long as they will provide for catching the drippings from the soap and also for the passage of air beneath the soap.

Also as shown in Fig. 6 the double-dented teeth are shown on both sides of the body, but obviously the variations in the arrangement of teeth previously described are applicable to the construction of valleys shown in Fig. 6.

The configuration of the holder and the configuration and number of the toothed ridges may be varied as desired.

Making the device of soft, flexible material, preferably rubber, results in these, among other, advantages:—The device will grip the hard and smooth surfaces of porcelain or enamelled washstands without liability of accidental displacement; if displaced or dropped in or upon the washstand the holder will not itself be injured or injure the washstand; it will hold the soap without

penetrating it, at least to such extent as to waste the soap or cause the soap to stick to the holder so tight as to require appreciable force to remove it; the flexible teeth retain the cake of soap, whether it be smaller than the holder or of the same size or larger; or in other words, it is not necessary to provide a soap-retaining rim of greater height than the intermediate teeth; and, finally, the teeth being flexible will insure a superficial contact with the soap, without penetration, quite sufficient to securely retain the soap in the holder when laid thereon and yet yield freely to loosen the hold on the soap when the soap is being removed for use.

Variations other than those herein specifically referred to are permissible within the principle of the invention and the scope of the following claims.

20 What I claim is:—

1. A soap holder, made of soft rubber, and having a serrated circumferential rim, and

intervening longitudinally extending serrated ridges.

2. A soap holder, made of soft rubber, and 25 having a serrated circumferential rim, and intervening serrated ridges, the rim and ridges being separated by valleys.

3. A soap holder, made of soft rubber, and having a serrated circumferential rim, and 30 intervening serrated ridges arranged on opposite sides of the body portion, the serrations being of different dentation on opposite sides.

4. A soap holder, made of soft rubber, and having circumferential and intermediate upstanding toothed portions spaced apart from one another and adapted to support a cake or piece of soap and permit the passage of air beneath it.

40 In testimony whereof I have hereunto set my hand this 29th day of October, A. D. 1923.

MARTIN BOCK.
